UNITED STATES PATENT OFFICE.

DAVID CROWELL, OF YARMOUTH, MASSACHUSETTS, ASSIGNOR OF ONE-HALF TO ANDREWS HALLETT, OF BATH, MAINE.

JIB-HANK.

SPECIFICATION forming part of Letters Patent No. 423,859, dated March 18, 1890.

Application filed October 11, 1889. Serial No. 326,670. (No model.)

To all whom it may concern:

Be it known that I, DAVID CROWELL, of Yarmouth, in the county of Barnstable, State of Massachusetts, have invented a certain new and useful Improvement in Jib-Hanks, of which the following is a description sufficiently full, clear, and exact to enable any person skilled in the art or science to which said invention appertains to make and use the same, reference being had to the accompanying drawings, forming part of this specification, in which—

Figure 1 is an elevation of my improved jib-hank; Fig. 2, an edge elevation of the same, and Fig. 3 a side elevation representing the hank as opened.

Like letters of reference indicate corresponding parts in the different figures of the drawings.

20 My invention relates to a detachable hank for securing a jib or other sail to the stays; and it consists in certain novel features, hereinafter fully set forth and claimed, the object being to produce a simpler, cheaper, and more effective device of this character than is now in ordinary use.

The nature and operation of the improvement will be readily understood by all conversant with such matters from the following 30 explanation.

In the drawings, A represents the hank considered as a whole. The hank is constructed of metal and is formed in two sections b d. These sections are of the same general shape, 35 and when closed form two loops or eyes f g for the stays and leaches. The sections overlap at their lower ends and are pivoted together at h. Their upper ends also overlap at i to prevent lateral movement and too great a strain on the pivot. The central portion j of the section b is elongated inwardly and has a hook k formed thereon. The corresponding portion of the section d is grooved at l to receive the portion j, and a hook m is 40 formed therein, adapted to take on said hook k when the sections are closed and lock them

firmly together. A pin p projects laterally from the hook k and a similar pin q from the companion m. The parts are so constructed that when the sections are brought together 50 considerable force is necessary to spring the hook m over the hook k, the elasticity of the metal permitting this, and yet offering sufficient resistance to the pressure of the ropes to prevent them accidentally separating. 55 When it is desired to separate the sections to remove the ropes, a marline-spike or similar article is inserted between the pins p q and employed as a lever to lift or spring the hook m upward sufficiently to release it from the 60 hook k, in a manner which will be readily understood by all conversant with such matters without a more explicit description.

It will readily be seen that by the use of my improvement the sails can be much more 65 quickly bent or unbent than when hanks of the ordinary construction are employed.

My invention may also be employed to take the place of a link in a chain when broken, or as hooks for the gaff-topsail sheets, mast-hooks, &c. As the greater portion of the strain from the ropes is borne by the ends of the loops f g where the sections overlap, as described, the sections are little liable to become unhooked. Moreover, the parts being 75 constructed of spring metal, it becomes necessary to exert a great strain on the hooks and at a point adjacent thereto, as the pins p q, before they can readily be separated.

Having thus explained my invention, what 80 I claim is—

The hank A, constructed in sections b d, pivoted at h and having their ends adapted to overlap, said section b having the hook k and pin p, and the section d provided with 85 the groove l and companion hook m and pin q, substantially as described.

DAVID CROWELL.
